(57) **CLAIM**

The ornamental design for an aircraft for air travel, as shown and described.

DESCRIPTION

FIG. 1 is a front elevational view of an aircraft for air travel showing our new design;

FIG. 2 is a rear elevational view thereof;

FIG. 3 is a right side view thereof;

FIG. 4 is a left side view thereof;

FIG. 5 is a top plan view thereof;

FIG. 6 is a bottom plan view thereof;

FIG. 7 is a perspective view thereof; and,

FIG. 8 is another perspective view thereof.

Any broken lines represent boundaries of the claimed design. The areas bound in broken lines illustrate portions of the article that form no part of the claimed design. The broken lines themselves do not form any part of the claimed design.
